UNITED STATES PATENT OFFICE.

RAYMOND LOPEZ, OF SAN DIEGO, CALIFORNIA, ASSIGNOR OF ONE-HALF TO ALFRED BUTTS, OF SAN DIEGO, CALIFORNIA.

CANDY-PULLING MACHINE.

1,414,743.

Specification of Letters Patent. Patented May 2, 1922.

Application filed May 10, 1920. Serial No. 380,079.

To all whom it may concern:

Be it known that I, RAYMOND LOPEZ, a citizen of the United States, residing at San Diego, in the county of San Diego and State of California, have invented certain new and useful Improvements in Candy-Pulling Machines, of which the following is a specification.

My invention relates to machines for pulling candy, more particularly that kind of candy known as taffy and more particularly the type of machine in which arm members are revolved relatively to each other for engaging the bulk of candy and the pulling of the same and the objects of my invention are: first, to provide a candy pulling machine of this class which is very sanitary and clean in operation as all of the working parts are inclosed; second, to provide a candy pulling machine of this class in which the supports are so positioned that different results are obtained with differently shaped supports for the arms, thus adding to the facility of the pulling; third, to provide a candy pulling machine of this class in which the supporting arms are so positioned that they form brace members in themselves so that the supports are stronger; fourth, to provide a candy pulling machine of this class which is very simple and economical of construction, durable, easy to operate and which will not readily deteriorate or get out of order.

With these and other objects in view as will appear hereinafter my invention consists of certain novel features of construction, combination and arrangement of parts and portions as will be hereinafter described in detail and particularly set forth in the appended claim reference being had to the accompanying drawings and to the characters of reference thereon which form a part of this application in which:

Figure 1 is a side elevational view of my machine complete; Fig. 2 is an end view at a right angle to that of Fig. 1; Fig. 3 is a top or plan view; Fig. 4 is a sectional view through 4-4 of Fig. 1 and Fig. 5 is a sectional view through 5-5 of Fig. 1.

Similar characters of reference refer to similar parts and portions throughout the several views of the drawings.

The plates 1 and 2, corner supports 3, supporting arms 4, revoluble supports 5,

arms 6, shafts 7, bevel gears 8, bevel gears 9, shafts 10, bevel gears 11, shaft 12, gears 13 and 14, intermediate shaft 15, sprockets 16 and 17, chain 18, sprockets 19 and 20 and motor 21 constitute the principal parts 60 and portions of my candy pulling machine.

The plate 1 forms the base and the plate 2 is supported above the same in spaced relation by means of the corner supports 3 thus forming a casing for the motor and main operating parts. Mounted on the plate 2 in the middle thereof, on opposite sides, are the supporting arms 4 which are hollow and positioned on an angle as shown best in Figs. 1 and 3 of the drawings 70 so that the axial line of said supporting arms are in alignment with the center of the casing formed by the members 1, 2 and 3. These arms are provided on their upper ends with hollow casing portions 4^a provided with caps 4^b and mounted in these casing members formed by the portions 4^a and 4^b is a shaft 7 journaled in opposite sides thereof. Mounted on one end of said shaft 7 is a bevel gear 8 supported by 75 ball bearings 8^a which form thrust bearings against the end of the casing. Mounted on the other end of the shaft 7 are the revoluble arms 5 which are in the form of double arm members, the one end being approximately double the length of the other and secured at the opposite ends are the arm members 6 which extend at right angles thereto so that the arm member 6 on the opposite supports 5 are positioned so that 90 they intersect with each other in their revolution. Mounted longitudinally in the supporting arms 4 and journaled therein are the shafts 10 on the upper ends of which are secured the bevel gears 9 which 95 intermesh with the gears 8. These shafts 10 extend down through the plate 2 and are supported by means of a journal 10^a in the lower end of the supports 4 and secured on the lower ends of these shafts 100

10 are the bevel gears 11 which intermesh with the gears 13 and 14 which are secured on a horizontal shaft 12 revolvably mounted in the center of the casing formed by the members 12 and 13 upon supports 105 12^a secured on the base plate 1. Upon this shaft 12 is secured a sprocket 16. Mounted on the base plate 1 are a pair of journal supports 15^a in which is journaled the shaft 15 upon which is mounted a sprocket 17 110

and connecting the sprockets 16 and 17 is a chain 18. Also mounted on the shaft 15 is another sprocket 19 upon which is mounted a chain 19^a which extends to and over a sprocket 20 secured on the motor 21 which motor 21 is secured on the base plate 1.

The operation of the candy puller is as follows: The motor revolving the sprocket 10 in turn revolves the sprocket 19, shaft 15, sprocket 17 and sprocket 16 thereby revolving the shaft 12 which in turn revolves the shafts 10 by means of the gears 11 and 13 and 14 which revolution of the shafts 10 revolves the shaft 7 by means of the bevel gears 8 and 9 and mounted on the shafts 7 are the supports 5 which carry the arms 6 and they are properly timed so that one of the arms 6 intersects the two arms on the opposite support 5 so that the body of the candy is engaged with each intersection and stretched by the relative movements of the arms to each other.

Though I have shown and described a particular construction, combination and arrangement of parts and portions I do not wish to be limited to this particular construction, combination and arrangement but desire to include in the purview of my invention the construction, combination and arrangement substantially as set forth in the appended claim.

Having thus described my invention

what I claim as new and desire to secure by Letters Patent is:

A candy machine, including a supporting casing, a single drive shaft revolvably mounted in said casing across the middle thereof, bevel gears secured to said shaft near each end, arms supported on said casing extending upwardly at an angle in opposite directions from each other and in alinement with said drive shaft, a shaft longitudinally journaled in each of said arms in angular position to said drive shaft, 45 bevel gears on their lower ends engaging the bevel gears on said drive shaft, housings on the upper ends of said arms, a shaft revolvably mounted in horizontal position in each of said housings, bevel gears connecting said angular positioned shaft with said horizontal shaft and a double crank arm secured to the inner ends of each of said horizontal shafts, the one extending only one-half the distance as the other and positioned opposite to each other and candy pulling arms secured to both extended ends of said arms so positioned and timed that one of the arms on one of said revolvable arms passes intermediate the other two arms 60 with their revolution.

In testimony whereof, I have hereunto set my hand at San Diego, California, this 3d day of May, 1920.

RAYMOND LOPEZ.
